COIN CHUTE

Clyde B. Gorton, Chicago, Ill., assignor to
C. B. McClellan, Chicago, Ill.Original application August 16, 1934, Serial No.
742,885. Divided and this application January
7, 1935, Serial No. 616

2 Claims. (Cl. 194—78)

This invention relates to a coin chute.

This application is a division of application Serial No. 742,885 filed August 6, 1934, Patent No. 1,987,292, dated January 8, 1935.

5 It is an object of this invention to provide an improved coin chute which is relatively simple and inexpensive in construction and efficient in use.

Another object of the invention is to provide 10 a new and improved coin chute adapted for use in conjunction with any coin controlled device or machine, such, for example, as vending machines, amusement game apparatus, etc.

An additional object of the invention is to 15 provide a coin chute which is constructed in such a manner that when a coin is inserted into the coin chute to operate an amusement game apparatus, vending device, or other mechanism associated therewith, the coin is moved into a

20 coin-receiving and displaying receptacle and is therein exposed through a sight opening to the proprietor or owner of the amusement apparatus or vending device with which the coin chute is associated so that the proprietor may readily 25 ascertain whether or not the player or operator of the device has inserted a proper coin into the chute to operate same.

Other objects will appear hereinafter.

The invention consists in the novel combination and arrangement of parts to be hereinafter 30 described and claimed.

The invention will be best understood by reference to the accompanying drawing, showing the preferred form of construction and in 35 which:

Fig. 1. is a perspective view of the new coin chute applied to the cabinet of a typical amusement device, vending machine, or the like;

Fig. 2 is a fragmentary sectional view on line 40 2—2 in Fig. 1, showing the coin slide in coin-receiving position;

Fig. 3 is a sectional view similar, to Fig. 2, but showing the coin slide in so-called full stroke position;

45 Fig. 4 is a side elevational view showing the coin slide in coin-receiving position; and

Fig. 5 is a sectional view on line 5—5 in Fig. 4.

A preferred form of the new coin chute is shown in Figs. 1 to 5 inclusive of the drawing 50 and is therein generally indicated at 10, the chute 10 being shown mounted in the end wall 11 of the cabinet of a vending machine, amusement device, or other coin-controlled device with which the coin chute may be associated.

55 The new chute 10 comprises a bracket 12

adapted for attachment to the wall 11 of the cabinet housing the associated mechanism. The chute 10 also includes a guide 16 and two independently movable members 18 and 70, the member 70 being in the form of a plunger and 5 the member 18 having the form of a flat bar.

Provided in the bracket 12 is a coin slot 14 which opens into an inclined chute 15 and the latter opens at its lower end into a coin-receiving aperture or pocket 69 which is provided by 10 the space between the two parts 18 and 70 (Fig. 2) so that when a proper coin 17 is inserted into the coin slot 14 it drops down the chute 15 and falls, in upright position, into the coin-receiving aperture or pocket 69 in front of the plunger 70 15 so that upon inward movement of the plunger 70 the coin 17 is moved from dotted line position "A" (Fig. 2) to full line position "B", (Fig. 3).

The inclined coin chute 15 has a yieldable 20 tongue 72 upon its upper wall (Figs. 2, 3, and 4); this tongue being attached at its upper end to the top wall of the coin chute 15 and being relatively free at its lower end.

The bar 18 is slidably projected into a slot 29 25 that is formed in the wall of the tubular member 70. Attached to the inner end of the bar 18 is one end of a resetting coil spring 19, the other end of the coil spring 19 being attached to the guide 16. 30

The bar 18 carries a downwardly projecting semi-circular ring 20 which is engageable with the hooked upper end portion 37 of a wire rod 21, this hooked end portion 37 of the rod 21 projecting through a slot 38 that is formed in the 35 bottom wall of the guide 16, while the other and lower portion end of the rod 21 is attached to a hinged gate 22. This gate 22 is hinged, as at 23, to a coin chute 24 which projects downwardly below the guide 16. The rod 21 has an 40 angled lower end portion 32 which projects upwardly through a movable bracket 33, the bracket 33 being attached to the gate 22. This portion 32 of the rod 21 also projects through a fixed bracket 34, the latter being attached to the 45 chute 24. A coil spring 35 is arranged upon the portion 32 of the rod 21 so as to urge the gate 22 into closed position.

Formed in the lower portion of the bracket 12 is a sight opening 25 in which is provided a 50 transparent plate or window 26, and this sight opening 25—26 cooperates with the gate 22 to form a coin-receiving and displaying receptacle.

Provided in the lower edge of the plunger 70 55 is a row of teeth 27 and pivotally mounted in

the guide structure 16 below the coin slides 18 and 70 is a two way dog 28, the teeth 27 and dog 28 providing a full stroke device, which is well known in the art.

- 5 Projecting through the slot 29 across the tubular plunger 70 and attached to the guide structure 16 is a pin 30. Arranged within the tubular plunger 70 and having one end attached to the pin 30 is a resetting coil spring 31.
- 10 It will be noted that in the present coin chute there are two coin slides, namely, the tubular plunger 70 and the bar 18, and that these two parts have a telescopic interfitting relationship, by reason of the slot 29, so that in the absence 15 of a proper coin in the coin-receiving aperture or pocket 69 inward movement of the plunger 70 will not move the slide bar 18.

However, when a coin of proper denomination, size, etc., is inserted into the slot 14 it falls 20 by gravity down the chute 15 into the coin-receiving aperture or pocket 69, and arranges itself in the inclined position "A" (Fig. 2) wherein it is supported by the bottom wall of the guide 16 and reclines against the arcuate bottom edge 25 of the lower wall 36 of the coin chute 15; and when the plunger 13 is pushed inwardly it engages the coin 17 and wedges the same into upright position between the plunger 70 and slide bar 18, thus latching the plunger 70 and slide 30 bar 18 together so that further inward movement of the plunger 70 will cause the latter and the slide bar 18 to move together as a unit and thus carry the coin 17 into position "B", Fig. 3 and as the coin slide 13—18—70 is moved 35 inwardly (right to left, Figs. 2, 3, and 4) the upper peripheral edge portion of the coin 17 engages the lower end portion of the tongue 72 and thereby pivots the latter (clockwise, Figs. 2 and 3, from full to dotted line position, Fig. 2) 40 whereupon the coin 17 passes by the tongue 72 and the latter by its own resiliency returns to its initial position (as in full lines Fig. 2), in which position it prevents the coin 17 from falling back onto the lower wall 36 of the coin chute 15.

45 When the coin slides 18 and 70 is pushed inwardly, the row of teeth 27 eventually pass beyond the full stroke dog 28, whereupon the then compressed resetting spring 31, and the then tensioned resetting spring 19, retract the plunger 50 70 and slide bar 18, respectively, thereby retracting the coin 17 (left to right, Fig. 3) along the bottom wall of the guide 16 until it engages the lower end portion of the member 72 which thereupon ejects the coin from the pocket 69 55 into position "C", Fig. 2. The coin 17 then falls off, or is discharged from, the guide 16 into the chute 24 and is guided by the gate 22 into the sight or display opening 25 wherein it is held by the window 26 and gate 22 so that the 60 proprietor of the vending machine, amusement device, or other mechanism with which the new coin chute is associated may readily see the coin the player has inserted into the chute to operate the same and thereby determine for 65 himself whether or not the same has been a coin of the proper size, denomination, etc.

The coin is held exposed to view in the sight opening 25 of the display receptacle 22—25—26 until another proper coin is inserted into the 70 coin slot 14 and chute 15, and the coin slides 18 and 70 are pushed inwardly, whereupon the semi-circular ring or lug 20 which depends from the slide bar 18, engages the upper and hooked end portion 37 of the rod 21. The rod 21 is thus 75 moved to open the gate 22, thereby allowing the

coin to fall from the sight opening 25—26 of the display receptacle into a suitable receptacle provided therefor in the cabinet of the mechanism with which the coin chute is associated.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

I claim:

1. A device of the character described, comprising: a guide; a pair of telescopically interfitting coin slides carried by the said guide and when in their normal or initial positions having a space therebetween providing a coin-receiving aperture or pocket; an inclined gravity feed coin chute arranged above the said guide and having communication at its lower end with the said coin-receiving pocket when the said coin slides are in coin-receiving position in such a manner that a coin disposed in said pocket will rest in an inclined position therein, relative to the vertical, and against the lower or bottom wall of said coin chute; the upper wall of said coin chute having its bottom edge terminating at a point above said pocket so that a coin disposed in said pocket may pass by the said bottom edge of said upper wall when the coin slides are moved away from coin-receiving position; and a resilient member arranged upon the upper wall of said coin chute; said resilient member having an upper end portion attached to the upper wall of said coin chute on the outer side thereof and having a yieldable lower end portion projecting downwardly below the said bottom edge of said upper wall so that when a coin disposed in said pocket is moved by said coin slides away from coin-receiving position it will engage the said yieldable portion of said member and, flexing the latter pass under the same and be prevented thereby from falling back against the lower wall of said coin chute; the said yieldable lower end portion of said resilient member serving to eject a coin from said pocket to a point below said slides when the latter are returned to their initial or coin-receiving positions.

2. A device of the character described, comprising: a guide; a pair of telescopically interfitting coin slides carried by the said guide and when in their normal or initial positions having a space therebetween providing a coin-receiving aperture or pocket; an inclined gravity feed coin chute arranged above the said guide and having communication at its lower end with the said coin-receiving pocket when the said coin slides are in coin-receiving position, in such a manner that a coin disposed in said pocket will rest in an inclined position therein, relative to the vertical, and against the lower or bottom wall of said coin chute; the upper wall of said coin chute having an arcuate bottom edge terminating at a point above said pocket so that a coin disposed in said pocket may pass by the said bottom edge of said upper wall when the coin slides are moved away from coin-receiving position; and a resilient member mounted upon the upper wall of said coin chute; said resilient member including an upper end portion attached to the upper wall of said coin chute on the outer side of the same and having a yieldable lower end portion projecting downwardly

below the said arcuate bottom edge of said upper wall so that when a coin disposed in said pocket is moved by said coin slides away from coin-receiving position it will engage the said yieldable portion of said member and flexing the latter, pass under the same and be prevented thereby from falling back against the lower wall

of said coin chute; the said yieldable lower end portion of said resilient member serving to eject a coin from said pocket to a point below said slides when the latter are returned to their normal or initial positions.

CLYDE B. GORTON.
